UNITED STATES PATENT OFFICE.

LOUIS GAITMAN, OF CHICAGO, ILLINOIS.

WINDOW SEAT.

Application filed April 20, 1922. Serial No. 555,770.

To all whom it may concern:

Be it known that I, LOUIS GAITMAN, residing at Chicago, county of Cook, and State of Illinois, a citizen of Russia, have invented certain new and useful Improvements in Window Seats, of which the following is a specification.

My invention relates to window seats, which are used in cleaning or painting the outside of windows and my object is to provide a seat for this purpose, which can be readily placed in position for immediate use, its construction being such as to afford the user perfect ease and freedom with absolute safety from collapse when in its operative position; or which can be folded into a very compact size when not in use. My invention consists in a window seat, having the characteristics of construction described by or included within the terms or language of the appended claims.

In the annexed drawings, forming part of this specification.

Fig. 1, is a central longitudinal section of my seat in operative position applied to the lower portion of a window frame, a temporary folding position being shown in dotted lines,

Fig. 2, is a top plan view of the window seat,

Fig. 3, is a view in perspective,

Fig. 4, is a side elevation of the lower portion of the window seat, illustrating another application thereof, and

Fig. 5, is a similar view of the window seat, showing it in a collapsed form.

Figure 6 illustrates a diagrammatic view of the window seat, showing its normal and extreme deflected positions.

My invention, in the form or embodiment shown in the drawings, and briefly described, comprises a relatively stationary frame, which is adapted to rest on the lower portion of the window frame and sill, a pivoted back support and a folding brace for rigidly supporting the back member in its operative position.

The stationary frame A, comprises a pair of horizontal and laterally spaced metallic strips or bars 10, and 11, connected together by means of a brace 12, and are provided at their front ends with downwardly extending portions 13, continued to form inwardly extending portions 14. These members 14, are provided with threaded openings for receiv-

ing clamping screws 15, adapted to engage and securely fasten the inner projecting portion 14, to the window frame 16. The bars 10, and 11, are preferably thinned rearwardly of the brace 12 for the purpose of 60 rendering them more readily flexible and near their rear ends extend downwardly as at 17, and outwardly again as at 18, thus forming a horizontal portion, which may rest on the outer portion of the window sill, 65 as shown in Figure 1, thereby forming a rigid support for the window seat.

For further supporting and preventing the accidental displacement of the window seat when in use, the outer ends of the horizontal portions 18, extend downwardly to form legs 19, bearing against the vertical outer side of the sill, thus effectively binding or wedging the frame against the outer end of the window sill, and providing a firm 70 support for the entire structure. The lower most portion of the downwardly extending leg member 19, is bent outwardly, forming a foot 20.

For pivotally supporting the back rest, I 80 provide a pair of outwardly disposed extensions or lugs 21, secured to the end portions or leg members 19, by riveting or welding.

The back rest B, is preferably constructed of a single strip of angle iron comprising a pair of parallel and spaced side members 22, and 23, and a connecting member 24. The connecting member 24, is curved outwardly to give added comfort to the user of 90 the seat. A strip 25, may be riveted to the lower portions of the side members 22, and 23, thereby more securely bracing the back rest.

I may also provide a fabric strip 29, near 95 the outer end of the frame 24, extending between the side members 22, and 23, and secured thereto for the purpose of providing a flexible back rest, whereby the back may be more comfortably supported, when in a, re- 100 clined position.

When in use, the back rest 21, is securely held in its reclined or operative position by means of a pair of brace members or links 26, and 27, which are pivoted to each other 105 as at 28, permitting the back 21, to be collapsed or folded, when moved in the direction of the arrows. The brace members 26, are pivoted to lugs or ears 30, which are located approximately midway along the 110

length of the said members 11, and 12, and secured thereto; whereas, the brace members 27, are pivotally mounted to the side members 22, and 23, of the back rest B, by means of bolts 31. The brace members 27, at their pivotal connection with the brace members 26, are provided with outwardly extending shoulders 32, for the purpose of engaging the adjacent brace members 26, to prevent the accidental collapse of the back rest.

10 It is readily seen that the pressure of the occupant against the back rest, is in an outward direction, and this will cause the front or hooked end of the seat to press firmly against the front extension of the window frame and hold the seat securely in place.

15 When it is desired to fold the window seat, as for storage or shipment, as is shown in Figure 5, I have provided removable bolts 31, so that the brace members 26 and 27, may be disconnected from the back rest and the entire window seat folded into a comparatively small space.

20 25 When the window seat is used in connection with a window having an outer sill of unusual length, as is shown in Figure 4, the foot 20, is adapted to rest upon the upper face of the sill.

30 35 It is, of course, understood that the window seat frame may be readily cast in one piece, as it is not intended to have this frame adjustable or collapsible, thereby securing for it the greatest amount of strength and rigidity, thus assuring the user of the maximum amount of safety which is so essential in a device of this kind. The entire window seat being so light and compact, it readily lends itself to be easily carried about, as from one window to another.

40 45 In the use of my invention, with special reference to Figure 1, the operator may readily sit upon the window sill itself although other forms of seats may be easily placed upon or between the spaced strips of the stationary frame.

50 55 Attention is particularly directed to the fact that in case the window ledge is slightly narrower than the window seat frame, or, in other words, if there is a space between the outer portion of the window ledge and the leg 19, this space will be taken up when the occupant leans against the back rest. It can be readily seen again referring to Figure 1, that the pressure against the back rest will have a tendency to move the leg 19, in a downward and inward direction through the medium of the lugs 21, pressing and binding the leg 19, against the ledge, due to the flexibility of the rearwardly extending portions of the stationary frame A, the lower ends of the links 26, acting as a pivot. This action 60 65 will, of course, more securely hold the front

hooked ends against the sill 16, and prevent their accidental displacement.

It is understood that my invention may be embodied in other forms than what is shown in the drawings, and the scope of 70 my protection is to be ascertained from the following claims.

I claim:

1. A portable window seat comprising a pair of spaced rigidly connected uncinate strips, adapted to be extended through a window and the hooked portions thereof engaged with the sill, the outer ends of said strips being flexible and embodying angular portions adapted for engagement with 75 the outer surface of a window ledge, a back rest pivotally connected to said strips at their outer ends, links pivotally connected to said back rest, corresponding links pivotally connected to said strips, and said first mentioned links for securely locking the seat to the window when in operative position.

2. A portable window seat comprising a relatively stationary frame adapted to extend through a window and rest on the sill thereof, consisting of a pair of laterally spaced strips, a transverse brace member, rigidly connecting the strips for maintaining their spaced relation, the front ends of the strips being provided with hooked members, and having threaded holes for the reception of clamp screws, the outer ends of said strips being flexible embodying angular portions adapted to rest upon the 100 upper surface of a window ledge and bent downwardly to engage the outer surface of said window ledge, for securely wedging said stationary frame to the window, and outwardly extending lugs secured to the 105 outer portion of said strips, a substantially U-shaped back rest pivotally mounted at its lower end to said lugs, a pair of links pivotally connected to each of said strips and to each leg of said back rest.

3. A portable window seat comprising a relatively stationary frame adapted to extend through a window and rest on the sill thereof, consisting of a pair of laterally spaced strips, a transverse brace member, rigidly connecting the strips for maintaining their spaced relation, the front ends of the strips being provided with hooked members, and having threaded holes for the reception of clamp screws, the outer ends of said strips embodying angular portions adapted to rest upon the upper surface of a window ledge and bent downwardly for engagement with the outer surface of said window ledge for securely wedging and 120 binding said stationary frame to the window, outwardly extending lugs secured to said leg members, a substantially inverted U-shaped back rest pivotally mounted at its lower end to said lugs, the upper end of 125 130

said back rest being curved outwardly that it may more readily conform to the user's back, a flexible strip secured to the side members of the back rest near the upper 5 ends thereof, and a pair of links pivoted to each other and pivotally mounted on each of said strips and to each leg of said back

rest, one of each pair of said links provided with a bent portion for engaging its mating link to prevent the collapse thereof. 10

In testimony whereof I hereunto affix my signature.

LOUIS GAITMAN.
